Primary Examiner — Robin V Webster(74) *Attorney, Agent, or Firm* — Shumaker Loop & Kendrick; Michael E. Dockins**CLAIM**

The ornamental design for a filter assembly, as shown and described.

DESCRIPTION

FIG. 1 is a front-right perspective view of a filter assembly showing my new design;
 FIG. 2 is a front elevational view thereof;
 FIG. 3 is a rear elevational view thereof;
 FIG. 4 is a left-side elevational view thereof;
 FIG. 5 is a right-side elevational view thereof;
 FIG. 6 is a top plan view thereof;
 FIG. 7 is a bottom plan view thereof; and,
 FIG. 8 is a front-left perspective view thereof.

The ornamental design which is claimed is shown in solid lines in the drawings. Features and portions in broken lines are presented for illustrative purposes and form no part of the claimed design.
